TIRE

Charles P. Wilcox, Mansfield, Ohio, assignor to
Spiegel, Inc., a corporation of Delaware

Application March 10, 1949, Serial No. 1,328

Term of patent 14 years

(Cl. D90—20)

To all whom it may concern:

Be it known that I, Charles P. Wilcox, a citizen of the United States, residing at Mansfield, in the county of Richland and State of Ohio, have invented a new, original, and ornamental Design for Tire, of which the following is a specification, reference being had to the accompanying drawing, forming part thereof.

Fig. 1 is a perspective view of a tire, showing my new design;

Fig. 2 is a fragmentary plan view thereof, diagrammatically showing the tread arrangement; and

Fig. 3 is a fragmentary elevational view of Fig. 1.

The dominant features of my design reside in that portion shown in full lines in the drawing.

I claim:

The ornamental design for a tire, as shown and described.

CHARLES P. WILCOX.
